CLAIM

I, claim the ornamental design for a locking food container, as shown and described.

DESCRIPTION

FIG. 1 is a top perspective view of the locking food container in a closed condition;

FIG. 2 is a top view of the locking food container in a closed condition;

FIG. 3 is a front side view of the locking food container in a closed condition;

FIG. 4 is a back side view of the locking food container in a closed condition;

FIG. 5 is a bottom view of the locking food container in a closed condition;

FIG. 6 is a left side view of the locking food container in a closed condition; and,

FIG. 7 is a right side view of the locking food container in a closed condition.

The broken lines shown in the drawings illustrate portions of the locking food container that form no part of the claim.
